Thomas M. K. Overland.

By *Henry Orth Jr.* Atty.

UNITED STATES PATENT OFFICE.

THOMAS M. K. OVERLAND, OF BESTUM, NEAR CHRISTIANIA, NORWAY.

HOLDER FOR GILLETTE AND THE LIKE RAZOR-BLADES.

1,289,888.

Specification of Letters Patent. Patented Dec. 31, 1918.

Application filed May 10, 1917. Serial No. 167,715.

To all whom it may concern:

Be it known that I, THOMAS M. K. OVERLAND, a subject of the King of Norway, residing at Bestum, near Christiania, in the 5 Kingdom of Norway, have invented certain new and useful Improvements in Holders for Gillette and the like Razor-Blades; and I do hereby declare the following to be a full, clear, and exact description of the invention, such as will enable others skilled in the art to which it appertains to make and use the same, reference being had to the accompanying drawings, and to letters or figures of reference marked thereon, which form a 10 part of this specification.

This invention relates to a blade holder for Gillette and the like razor blades.

The object of the invention is to provide a blade holder of this class, composed of 20 only two simple and cheap sheet metal parts slideable relatively to each other in such manner that the handle portion in one position is adapted to be used as a handle, and in another position serves as a protector for the 25 blade edge.

The invention is illustrated in the accompanying drawing.

Figure 1 is a side view of the holder and Fig. 2 a sectional view on line A—A, Fig. 1. 30 Fig. 3 illustrates a modified form of the handle portion.

1 is a piece of elastic sheet metal bent double to the cross sectional form shown in Fig. 2. In one side of the same are punched 35 out conical tongues 4, adapted to fit into the holes of a Gillette or similar razor blade 3, the ends of said tongues fitting into holes or pockets in the opposite part of the sheet metal plate and thereby locking the blade 3 in position between the two upper portions 40 of the piece 1, which are kept pressed against each other by the spring action of the sheet metal.

Below these tongues 4 and the opposite 45 holes the piece 1 bulges out into a rectangular, oval or other non-circular cross section, as shown on Fig. 2, and into the sleeve or guide formed by this portion of the piece 1 is fitted the handle 2, likewise of sheet metal 50 and bent into corresponding cross sectional form.

In the preferred form shown in the drawings this handle 2 besides serving as a handle, also serves as a protector or screen for 55 the edge of the razor blade 3, and also as a

means for spreading the holder for the removal and insertion of blades.

In Fig. 1 the handle 2 is shown slid half-way over the blade 3, its slot 5 fitting around the same in such way as to protect its edge 60 completely when moved to its extreme left position.

When the blade is to be removed, this is effected by turning the handle 2 axially whereby the two sides of the piece 1 will be 65 pressed outward, thereby widening the slot 6 between them, and drawing the tongues 4 out of the opposite holes of the blade 3, thereby enabling the blade to be removed and replaced by a fresh one. 70

In Fig. 1 the relative movements of the parts 1 and 2 are limited by a collar 7 and a knob 9, pressed out at the respective ends of the handle portion 2.

In the modified form of the handle shown 75 in Fig. 3 the movement of the handle is limited by aid of the tongues 8 turned up from the main body of the handle.

I claim:

1. A collapsible razor comprising a holder 80 of resilient sheet metal adapted to grip the razor blade between its sides and having an integral sleeve portion at one end, and a handle movable in said sleeve portion having a slot to receive the edge of the blade when 85 the razor is collapsed.

2. A razor blade holder comprising a re-silient sheet-metal member adapted to grip a blade between its sides and having a laterally projecting sleeve portion at one end 90 thereof, and a tubular member movable longitudinally in the sleeve and adapted to form a handle for the sheet metal member, said tubular member having a longitudinal slot arranged to receive the lower portion 95 of a blade when the tubular member is moved in the sleeve under the sheet metal member.

3. A razor blade holder comprising a re-silient sheet-metal clamp adapted to hold a 100 blade, and an operating handle connected with said clamp adapted to spread the latter to release a blade therefrom.

4. A razor blade holder comprising a re-silient sheet-metal clamp having sides adapted to grip a blade between them, and having a sleeve portion, and an operating handle in the latter adapted to spread the clamp to release a blade therefrom. 105

5. A razor blade holder comprising a re- 110

silient sheet-metal clamp having sides adapted to grip a blade between them, and having a sleeve portion, and an operating handle rotatable in the latter and adapted 5 to spread the clamp to release a blade therefrom.

6. A razor blade holder comprising a resilient sheet-metal clamp having sides adapted to grip a blade between them and having 10 a non-cylindrical sleeve portion, and a tubular operating handle axially movable in said sleeve and having a cross section corresponding to the cross section of the sleeve, for the purpose specified.
- 15 7. A razor blade holder comprising a resilient sheet-metal clamping member having sides adapted to grip a blade between them and formed with tongues arranged to fit into

apertures in a blade, a laterally projecting non-cylindrical sleeve formed at one end of 20 the clamping member, a non-cylindrical tubular member arranged parallel to the lower edge of the clamping member and slidably mounted and axially movable in said sleeve, said tubular member having a longitudinal 25 slot arranged to receive the lower portion of a blade when the tubular member is moved in the sleeve under the clamping member.

In testimony that I claim the foregoing 30 as my invention, I have signed my name in presence of two subscribing witnesses.

THOMAS M. K. OVERLAND.
